GRID FOR CONVEYER BELT SYSTEMS

Frank Parker, Edmonds, Wash.

Application July 19, 1939, Serial No. 285,453

2 Claims. (Cl. 209—257)

The invention relates to a screening apparatus and more especially to a cleaning grid for conveyer belt systems.

The primary object of the invention is the provision of a grid of this character wherein the same is disposed over a conveyer belt adapted for moving material such as loose dirt and thus dirt can be loaded onto the belt with rocks of larger sizes removed from the dirt in its delivery onto the belt, thereby enabling the proper handling of the dirt for the conveying of the same to a point for distribution or deposit.

Another object of the invention is the provision of a grid of this character wherein the rock removed from the dirt as the latter is loaded upon a conveyer belt will be caused to gravitate into chutes at opposite sides of the grid whence such rock can be delivered onto trucks for disposition thereof.

20 A further object of the invention is the provision of a grid of this character wherein the same is novel in its entirety and assures the requisite screening of material such as loose dirt to remove heavy solid particles as for example rocks, 25 of determined sizes to rid these from the load upon the belt thereby enabling the convenient handling of the load and the rock will be cleaned from the grid should the same become lodged therein and in this manner eliminating the clogging of such grid in the use of the same.

20 A further object of the invention is the provision of a grid of this character wherein it is made up of a plurality of sections, these being selectively cleaned to avoid clogging thereof in the 35 use of the same.

A still further object of the invention is the provision of a grid of this character wherein dirt when loaded into trucks can be conveniently dumped onto the grid for the cleaning of the dirt 40 during the deposit thereof onto a conveyer belt and in this manner the entire grid can be maintained clean for screening operations.

A still further object of the invention is the provision of a grid of this character which is 45 comparatively simple in construction, thoroughly reliable and efficient in operation, susceptible of being cleaned with dispatch and inexpensive to manufacture and install.

50 With these and other objects in view, the invention consists in the features of construction, combination and arrangement of parts as will be hereinafter more fully described in detail, illustrated in the accompanying drawings, which disclose the preferred embodiment of the invention

and pointed out in the claims hereunto appended.

In the accompanying drawings:

Figure 1 is an elevation partly in section of a grid and adjuncts constructed in accordance with the invention. 5

Figure 2 is a sectional view taken on the line 2—2 of Figure 1 looking in the direction of the arrows.

Figure 3 is a sectional view taken on the line 3—3 of Figure 1 looking in the direction of the 10 arrows.

Figure 4 is a perspective view of the driving and control mechanism for the grid and shown in association with an electric circuit and power motor operated by current supplied therefrom, 15 the circuit being diagrammatically illustrated.

Figure 5 is a fragmentary vertical transverse sectional view showing in detail the ratchet latching mechanism employed with the grid.

Similar reference characters indicate corresponding parts throughout the several views in the drawings. 20

Referring to the drawings in detail, A designates generally a conveyer belt horizontally arranged and driven in any suitable manner for 25 conveying loose material from a receiving point to a delivery point. Above this conveyer belt A is a substantially hopper-shaped feeder trough 10, being permanently built in its superposed relation to said belt in a stand 11. Overhanging this trough 10 and built within the stand 11 is a grid 30 constituting the present invention and herein-after fully described.

The grid involving the invention comprises end pieces or plates 12 and 13 respectively and intermediate pieces or plates 14. These plates 12, 13 and 14 are perpendicularly arranged and built within the stand 11 for permanency, being peaked and having fitted therewith a central ridge piece 15. The end and intermediate pieces 12, 13 and 14 are spaced apart, yet the said pieces 14 are in contiguous relation to each other for providing a gap 16 therebetween. The ridge piece 15 which is a partial crown for the grid extends longitudinally centered with respect to the pieces 12, 13 and 14. 40

Between the pieces 12—14 and 13—14 respectively, are grouped grid bars 17 which are arranged in upward convergent relation to each other at opposite sides of the ridge piece 15 and 50 are movably held within the stand 11 for the screening of loose material, such as dirt dumped thereonto from trucks or other load carriers, not shown, these being adapted to be driven onto platforms 18 for dumping purposes. 55

The grid is for the purpose of removing rocks from the loose material, that is to say, dirt when dumped thereon from the trucks or carriers upon the platforms 18. These platforms 18 are at opposite sides of the ridge piece 15. The platforms 18 are permanently built on the stand 11 which with the grid constitutes a bunker. The loose dirt screened between the bars 17 gravitates into the hopper-like trough 10 and thence therefrom onto the conveyer belt A for the loading of the same and the carrying of this load to a point of distribution or deposit.

At opposite sides of the stand 11 below the grid bars 17 with relation to the lowermost ends thereof are inclined chutes 19 which are receptive to rocks or other solid matter removed from the loose dirt by the grid in that these particles, such as rocks or the like will gravitate from the grid into the said chutes whence the same will be loaded into a truck or other conveyer on discharge from the chutes 19.

Arranged below the grid bars 17 are stationary grid combing or cleaning units, each including a series of spaced bars 20 fixedly held in their spaced parallel relation to each other by inner and outer longitudinally disposed angle rails 21, these being joined to the bars 20 which through such arrangement are adapted to have enter therebetween the grid bars 17 for clearing solid matter, rocks or the like when clogging the spaces between said grid bars. The bars 17 in series are adjusted in a manner presently described for grid cleaning operation. The units having the bars 20 are arranged in corresponding sloping relation to the grid bars 17 but are disposed beneath the same.

Carried by the pieces 12, 13 and 14 in underlying close relation to the grid bars 17 are inner and outer guide pulleys 22 and 23 respectively over which are trained lift cables 24, these having branches 25 and 26 respectively which are terminally connected to eye members 27 on swinging cranks 28 connected by pivot shafts 29 to the rails 21 and to rocking shafts 30. The swinging cranks are associated with the shafts 30 and on the swinging of said cranks the units having the bars 17 will move toward or away from the bars 20 and in these movements remove clogged or wedged material in the grid so that the latter will be clean for screening of loose dirt.

Arranged longitudinally and centrally of the stand 11 are spaced parallel power shafts 31 and 32 respectively, the pieces 12, 13 and 14 being provided with clearances for the said power shafts which pass therethrough. These power shafts are journaled in bearings 33 suitably supported in the stand 11. Splined on the power shafts 31 and 32 are shiftable clutch members 34 for turning with the said shaft and engageable with or disengageable from these clutch members are companion clutch members 35, being loose upon the shafts 31 and 32 respectively. These clutch members 35 have cable spools 36 arranged in pairs for the respective combing units having the bars 20, those of the pairs being arranged at opposite ends of such units and operate the cables 24 which are adapted to be wound on and unwound from said spools in the working of the grid. On the winding of the cables 24 on these spools 36 the series of bars 17 are moved with relation to the bars 20.

The clutch members 34 of the pairs associated with the spools 36 are thrown to clutching and declutching positions through the use of throw rods 37 pivoted at 38 and 39 respectively and also

pivoted at 40 to throw levers 41, these being conveniently located to a platform 42 in the stand 11 for an operator of the machine, being hand manipulated. The levers 41 have connected thereto coil springs 43 which normally hold the members 34 in declutching positions. When the members 34 are in clutching position with the companion members 35 the spools 36 are rotated.

The shafts 31 and 32 are seated with meshing driven gears 44 for the operation thereof in unison with each other and rotate reversely one with the other, while the shaft 31 has fitted thereto a worm screw pinion 45 meshing with a worm feed gear 46 operated from the power shaft of a power motor 47. The motor is suitably supported in the stand 11 and is in an electric circuit having the current wires 48 and 49 respectively. This circuit has arranged therein a push button switch 50, a magnetic switch 51 and a cam operated switch 52 respectively, the electromagnet of this magnetic switch 51 being indicated at 53 and is arranged parallel with the circuit. The cam actuated switch 52 has its operating cam 54 fixed to the power shaft 31 so that when the said power shaft has completed a single cycle of rotation the switch 52 operates to open the circuit to the motor 47 for the stopping thereof while a hand push button switch 50 functions as a starting switch for the said motor 47. The rotation of the shafts 31 and 32 operate the units having the bars 17 so that the cleaning of the grid will be accomplished. A selected unit having the bars 17 is brought into operation by actuating the lever 41 for the clutching of the clutch member 34 with the companion clutch member 36, being required that the said lever 41 be held in a thrown position to maintain clutching engagement of these members 34 and 35 with each other. On the release of this lever 41 the spring 43 attached thereto becomes active for the declutching of the members 34 and 35.

Each member 35 is formed with a ratchet gear 55 with which coacts a ratchet pawl or dog 56 fixed to a rocking shaft 57. In association with this pawl or dog 56 is a coiled tensioning spring 58 which functions to normally hold the pawl or dog in engagement with the ratchet gear 55 and thereby locking the member 35 against rotation in one direction by allowing it to rotate in a reverse direction so that when a unit having the bars 17 has been moved it will be latched until the pawl or dog 56 is released from the gear 55. The shaft 57 having the pawl or dog fixed thereto carries a foot treadle 59 so that on depressing the latter the pawl or dog 56 can be released from the gear 55 whereupon the unit having the bars 17 will gravitate to a lowered position due to the inherent weight thereof.

It is desirable to have the power motor 47 equipped with a brake mechanism, not shown, to prevent coasting thereof on the opening of the circuit to this motor.

The treadles 59 are located contiguous to the platform 42 for manual operation thereof and these treadles in a group enable selected control of the unit having the bars 17. The motor 47 on the starting thereof is active until the circuit thereto is opened by the cam switch 52 which controls the opening and closing of the said switch on the rotation of the shaft 31 as will be apparent from Figure 4 of the drawings.

What is claimed is:

1. The combination of a stand having a discharge hopper, mechanically raised and gravity

lowered movable grid bars arranged in spaced parallel relation to each other above said hopper, groups of spaced parallel stationary cleaner rails cooperating with the grid bars, mechanism movably suspending the groups of movable grid bars whereby the latter will approach and recede from said cleaner rails, platforms overhanging portions of said grid bars for dumping trucks in discharging loose material onto said bars, chutes at opposite sides with respect to the hopper and accommodating material gravitated from said grid bars, mechanism having connection with the groups of movable grid bars for selectively moving the same, power means associated with said mechanism, electrical equipment controlling the operation of said power means, and manually controlled ratchet gear and pawl connections

associated with the groups of grid bars for effecting the mechanical raising of the latter and the releasing of such bars for gravity lowering of the same.

2. The combination of a discharge hopper, groups of normally stationary grid bars disposed over said hopper, groups of spaced parallel stationary cleaner rails positioned below said groups of grid bars, each cleaner rail being vertically aligned with the space between two adjacent 10 grid bars, means operable at the will of an operator for independently lowering said groups of grid bars to the level of said cleaner rails, means for raising said grid bars to their normal raised position, and means for maintaining said 15 bars stationary in their normal raised position.

FRANK PARKER.
